Primary Examiner—Holly H. Bayham
Attorney, Agent, or Firm—Steven R. Scott[57] **CLAIM**

The ornamental design for the blade of a roof stripping spade, as shown and described.

DESCRIPTION

FIG. 1 is a side view of the blade of a roof stripping spade with the opposite side being a mirror image thereof;

FIG. 2 is an enlarged side elevational view thereof;

FIG. 3 is a bottom view thereof;

FIG. 4 is a front elevational view thereof;

FIG. 5 is a rear elevational view thereof;

FIG. 6 is a fragmented sectional view of the fulcrum thereof taken along line 6—6 of FIG. 2; and,

FIG. 7 is a fragmented sectional view of the fulcrum thereof taken along line 7—7 of FIG. 3.

The broken line showing of a handle, scraper and a surface is for illustrative purposes only and forms no part of the claimed design.
